[57] CLAIM

The ornamental design for a ball, as shown and described.

DESCRIPTION

FIG. 1 is a perspective view of a ball showing my new design;

FIG. 2 is a front elevational view of the ball;

FIG. 3 is a top view of the ball;

FIG. 4 is a left side elevational view of the ball, the right side elevational view being identical to this view;

FIG. 5 is a bottom view of the ball;

FIG. 6 is a rear elevational view of the ball; and

FIG. 7 is a bottom view of the ball turned 90 ninety degrees from the view shown in FIG. 5.
